Inventor
RUSSELL HOPKINSON

UNITED STATES PATENT OFFICE.

RUSSELL HOPKINSON, OF NEW YORK, N. Y., ASSIGNOR TO THE GOODYEAR'S INDIA RUBBER GLOVE MFG. CO., OF NAUGATUCK, CONNECTICUT, A CORPORATION OF CONNECTICUT.

INFLATABLE VULCANIZED ARTICLE.

Application filed July 28, 1926. Serial No. 125,380.

This invention relates to an inflatable vulcanized article, more particularly to a pneumatic surf board, and is a division in part of my co-pending application Serial No. 643,563, filed June 5, 1923.

The use of surf boards by bathers at the various beaches is becoming quite common. In using such boards the bather walks out into the water as far as possible and upon the approach of a breaker launches himself upon the board and in the direction of the shore just as the crest of the breaker reaches him, the object being to maintain the board in such a position that it tends to slide by gravity down the forward face of the wave, but due to the inward movement of the wave the board is carried forward continually until the shore is reached. As commonly constructed these boards are made of wood or other rigid inmaterial and their use is therefore attended with some risk, owing to the likelihood of the user and those in the vicinity being struck by the board. Moreover as the boards are somewhat bulky they are inconvenient to carry when not in use. It has been proposed to make a pneumatic surf board in which the outer casing is divided into compartments and elongated inflatable bags inserted into the compartments, secured in place and then individually inflated. Such boards are relatively heavy, expensive, and considerable time is required to assemble them.

An object of my invention is to provide a light relatively rigid inflatable article of vulcanized material.

Another object is to provide an integrally united inflatable article of vulcanized material which may be folded or rolled into small compass when deflated.

A still further object is to provide a light, safe and easily handled pneumatic surf board.

For a detailed disclosure of the invention reference is had to the accompanying specification and drawings, in which latter,

Fig. 1 represents in sectional perspective a partially completed pneumatic article according to one form of the invention;

Fig. 2 is a similar view of the article in a

more or less diagrammatic form at a later stage in its manufacture;

Fig. 3 is a similar view of the finished inflated article;

Fig. 4 is a diagrammatic view illustrating another form of the invention in its initial stages;

Fig. 5 illustrates a later stage of said modified form;

Fig. 6 represents a finished article of the modified form;

Figs. 7 and 8 are fragmentary illustrations of another modification in two stages of its manufacture;

Figs. 9, 10, 11 and 12 each illustrate further modifications of the invention;

Fig. 13 is a plan view of a finished surf board;

Fig. 14 is a side elevation thereof;

Fig. 15 is a front view;

Fig. 16 is a sectional perspective of a modified strengthening member; and

Fig. 17 is a sectional perspective of an article using the construction shown in Figure 16.

Referring to the form shown in Figures 1 to 3, a bottom sheet 1 of any suitable unvulcanized rubberized fabric is laid in the flat, which sheet may be cemented on its upper face along its central portion and from thence to its left-hand edge. A spacing strip of rubberized fabric 2 is then laid on the central cemented portion and rolled down. Another strip 3 of rubberized fabric of greater width is then superposed on the strip 2 with its edges projecting at each side of the latter, and the projecting portion 4 which overlies the cemented portion of the sheet 1 is rolled down into union with the latter. A strip 5 similar to the strip 3 is laid on the strip 3 in a shingled arrangement and that portion 6 of it which overhangs the cemented portion of the sheet 1 is rolled into contact with the latter. A strip 7 similar to the strips 3 and 5 is next placed in position in the same manner and its overhanging portion 8 rolled down into connection with the sheet 1. If the sheet 1 is of greater width this process will of course be continued until the edge of the sheet is

100

reached. The strips 2, 3, 5 and 7 may be of fabric frictioned on its lower side only, in which case the frictioned portions of the strips will not adhere to the uncoated fabric surfaces which they overlie. However, it may be desirable to friction both sides of the strips and in this case all portions of the strips which are not to be adhesively united may be dusted with starch or talc. The right-hand side of the sheet 1 may then be cemented and a series of strips joined thereto in the same manner but with the overlap oppositely directed. Those portions of the strips which are to be united to the sheet 1 may of course also be cemented. Each strip is then exactly doubled upon itself as shown diagrammatically in Figure 2 and at the center a spacing strip 12 is laid on exactly above the spacing strip 2. A top sheet 13 which may have its under surface cemented is then united to the portions 9, 10, and 11 of the doubled over strips which overlie the respective portions 8, 6 and 4, and it is also united to the top spacing strip 12. By reason of the extended area of connection between the strips 3, 5 and 7, and the top and bottom said strips are very strongly connected to the top and bottom. The top sheet 13 and bottom sheet 1 are then joined all around their edges in any suitable manner as by overlapping, and a valve inserted at a suitable place, which in the case of a pneumatic surf board may be inserted at the rear as shown at 14 in Figure 13. The article may then be very lightly inflated to the form shown in Figure 3 and cured. As the usual heat of vulcanization renders the stock so soft that it tends to run or become quite plastic it is preferable to use a stock containing one of the so-called "cold cure accelerators". When using such a stock the article may be left to cure at ordinary temperatures, or if it is desired to hasten the process it may be heated for a short time at a relatively low temperature, for instance 150° F. While in the present form of the invention the parts have been described as being cemented together it is obvious that the green rubber parts may be merely adhesively united by rolling and the final cure relied on to permanently unite them in the manner commonly depended upon in making plied up rubber articles. Moreover, if desired, the article may be built up of vulcanized stock with the use of an ordinary or a self curing cement to secure the parts.

In the case of some articles such as mattresses, cushions, etc., it may be desired to make them of the same thickness throughout, but in the case of the surf board it is preferred to have the greatest depth at a point between $\frac{1}{4}$ and $\frac{1}{3}$ the length from the bow, and decrease the depth from this point to the bow and stern. To accomplish this purpose the strips 2, 3, 5 and 7 can be

made of a width regularly decreasing, or the strips may be made of a uniform width and the portion of the strip which is cemented to the top or bottom made of increasing width from the point of greatest depth, or the two methods may be combined.

In a modified form of the invention as illustrated in Figures 4 to 6 the bottom and top sheets 15 and 17, respectively, are coated with cement to form adhesive spaced strips 16 correspondingly disposed on the upper and lower sheets. Tubes 18 which may be formed of rubberized fabric are flattened so as to form superposed plies, and the flattened tubes laid centrally on the cemented strips 16 of the bottom sheet and rolled down. The top sheet 17 is then disposed so that its cemented strips 16 are located centrally of the top plies of the flattened tubes, the sheet rolled down and the edges of the sheets joined by lapping or otherwise to completely inclose the article, which when inflated has the form shown in Fig. 6. In this modification when it is desired to make the article of greater depth at any point the tubes 18 may be made tapering or conical with the greatest diameter at the point where the greatest depth is desired, or instead the cemented area which joins each tube to the sheet may be made of a gradually increasing width from the point of greatest depth.

In Figures 7 and 8 there is shown a further modification of the invention which is very similar to that shown in Figures 1-3. In this form the bottom sheet 19 is laid flat as before and the spacing strip 20 is cemented to the bottom sheet as in the form shown in Figure 1. However, the spacing strip is made of a greater width and its edges are folded over as shown at 21. The strips 22 are disposed on the bottom in shingled arrangement as in the form shown in Figure 1, but the strips are of somewhat greater width and at the edges are folded in as shown at 23. When the strips are doubled over the folded top edge 23 is disposed directly over the lower one. The central top spacing strip 24 is of a width corresponding to the bottom strip 20 and has its edges turned under as shown at 25. The top sheet 26 is then cemented and rolled down in exactly the same manner as in the form shown in Figures 1-3. It will be seen from an inspection of Figure 8 that in the finished article the strips 22 form strengthening and stiffening ribs exactly as do the strips 3, 5, and 7, but that in addition the portions of the ribs which are connected to the top and bottom also extend downwardly and upwardly, respectively, on the vertical portions of the adjoining ribs, thereby both further strengthening the connection between the ribs and the top and bottom and also making the ribs stiffer. The extended

ends of the central spacing strips 20 and 24 perform a similar function for the ribs adjoining them. In addition, in both the form shown in Figures 1-3 and that shown in Figures 7 and 8, the top and bottom are in effect made two ply by reason of the spacing strips and attaching ends of the connecting strips, thereby greatly strengthening the article.

10 A simplified form of the invention is shown in Figure 9, in which the top and bottom sheets 27 and 28 are united along narrow spaced areas 29 by rolling them into adhesion or by both cementing and rolling them so that in the finished and cured article the top and bottom will be firmly united at these points. When inflated it assumes the shape as illustrated in the figure.

The form shown in Figure 10 is similar to that in Figure 9 and the top and bottom sheets 30 and 31, respectively, are united along narrow spaced areas 32 in the same manner as in the form shown in Figure 9, but strengthening members such as the 25 stitches 33 are disposed in the joined areas, and the stitches covered by gum strips 34. It is obvious that instead of the stitches, staples or any other suitable fastenings may be employed.

30 In the form shown in Figure 11 the top sheet 35 and bottom sheet 36 are united along narrow spaced areas by means of the interposed small tubes 37 of rubberized fabric. These tubes are flattened out when the 35 parts are rolled together and the superposed plies furnish a relatively extended uniting area to the top and bottom sheets.

In the form shown in Figure 12 the top sheet 38 and bottom sheet 39 are also 40 united along narrow spaced areas by interposed strengthening and stiffening members. Each stiffening member is formed of two superposed strips 40 of rubberized fabric which may be rolled into adhesive contact on their center line and also stitched or otherwise secured along this line as shown at 41, while the remainder of the contacting faces of the strips 40 are kept from adhering by the use of starch or talc. In making 45 an article according to this modification of the invention the bottom sheet is laid flat and a series of the strengthening members disposed on the bottom sheet in spaced relation, the bottom face of the lower strip 40 being cemented. The strengthening members 50 are then rolled down on the bottom sheet, the upper face of the top strengthening member cemented, and the top sheet rolled down. The edges of the top and bottom sheets are then joined as before and the 60 article cured. This modification also provides an extended joining area between the strengthening member and the top and bottom sheets. It is obvious as before stated 65 that either or both of a pair of surfaces to

be joined may be cemented or the natural adhesion may be relied upon while building up the parts.

In Figures 16 and 17 still another modification of the manner of forming the 70 strengthening ribs is shown. In this modification ribs 42 formed of fabric or any other suitable material are joined by seams 43 to top and bottom attaching strips 44, or in any other suitable manner. The ribs 75 42 in this instance need not be frictioned or otherwise coated with rubber, and the strips 44 need only be frictioned or rubber coated on their outer or attaching faces. In assembling an article according to this modification the bottom sheet 46 of rubberized fabric is laid down, and the strengthening ribs and connected attaching strips are folded as shown in Figure 17 and laid on the bottom sheet in spaced relation. The frictioned outer or contacting faces of the bottom attaching strips 44 may be merely rolled into adhesive contact with the rubberized sheet 46 or cement may be used in addition. The top sheet 45 is then laid on 80 and connected to the upper attaching strips 44 in the same manner, and the top and bottom sheets 45 and 46 then joined at their edges. This form of the invention provides a very strong union between the strengthening ribs and the top and bottom of the article without perforation of said top and bottom, thereby lessening any chance of leakage through sewed seams.

It will be seen that by my invention a 100 pneumatic surf board is provided which in the finished article is a unitary body, and which can be simply and economically built up in the flat from the prepared parts. By merely increasing the air pressure a surf 105 board of any desired stiffness may be obtained, but if desired stiffening members may be inserted in the vertical ribs or in the top and bottom. By deflating the article it can be rolled into small compass for 110 shipping or storage. When inflated the vertical ribs 3, 5 and 7 as shown in Figures 1 to 3, or the various connections shown in the modified forms, act as strengthening and connecting members and also to stiffen the 115 board.

While the invention has been particularly shown and described as applied to a pneumatic surf board it is obvious that it is not so limited in its application and that it can 120 be used for making pneumatic floats of various kinds, mattresses, cushions, and many other articles, and it is therefore not desired to limit the invention otherwise than as set forth in the appended claims.

Having thus described my invention what I claim and desire to protect by Letters Patent is:—

1. An inflatable article of vulcanized material comprising spaced top and bottom 130

- sheets of vulcanized material and spaced ribs extending between the top and bottom, said ribs having extended attaching portions joined to said top and bottom. 5. 2. An inflatable vulcanized article comprising top and bottom sheets of vulcanized material joined at their edges and spaced ribs having extended attaching portions united to the top and bottom sheets, the edge 10 portions of said attaching portions being angularly disposed and united to an adjacent rib. 3. An inflatable vulcanized article comprising top and bottom sheets of vulcanized material joined at their edges and spaced ribs having extended attaching portions united to the top and bottom sheets, the edge 15 portions of said attaching portions being angularly disposed and united to an adjacent rib, 20 and the attaching portions of the ribs extending in opposite directions from the center line of the article. 4. A pneumatic surf board comprising a top and bottom of vulcanized material and 25 spaced interposed longitudinally extending connecting and stiffening ribs, the whole being integrally united by vulcanization. 5. A pneumatic surf board comprising a top and bottom united at their edges, and 30 spaced interposed longitudinally extending strengthening and stiffening ribs attached to the top and bottom, the whole forming a unitary body of vulcanized material united by the act of vulcanization. 35 6. A pneumatic surf board comprising a top and bottom of vulcanized material united at their edges, and spaced interposed strengthening ribs connected to the top and
- bottom, said ribs decreasing in depth from an intermediate portion of the board to- 40 wards its bow and stern. 7. A pneumatic surf board comprising a top and bottom of vulcanized material, and spaced interposed strengthening ribs united by vulcanization to the top and bottom, said 45 ribs decreasing in depth from an intermediate portion of the board towards its bow and stern, and openings between the passages formed by said ribs and top and bottom. 8. A pneumatic surf board comprising a spaced top and bottom of vulcanized material, the spacing of the bottom from the top decreasing towards the bow and stern of the board, spaced interposed ribs united by 50 vulcanization to the top and bottom, and means whereby the board may be inflated. 9. A pneumatic surf board comprising a top and bottom of rubberized fabric, and spaced longitudinal strengthening ribs of 55 rubberized fabric united by vulcanization to the top and bottom, said ribs decreasing in depth from an intermediate portion of the board toward the bow and stern. 10. A pneumatic surf board comprising a 60 top and bottom of rubberized fabric, spaced interposed strengthening ribs of rubberized fabric, said ribs having extended attaching portions joined to the top and bottom by vulcanization, the edges of the top and bottom being joined and said ribs terminating short of said edges. 65
- Signed at New York, county of New York, State of New York, this 26th day of July, 1926.
- RUSSELL HOPKINSON.
